O. MARTIENSSEN
ARRANGEMENT ON GYROCOMPASSES FOR PREVENTING ERRORS DUE TO
ROLLING OF THE VESSEL
Filed Aug. 31, 1921

*Inventor.
Oscar Martienssen*

UNITED STATES PATENT OFFICE.

OSCAR MARTIENSSSEN, OF KIEL, GERMANY.

ARRANGEMENT ON GYROCOMPASSES FOR PREVENTING ERRORS DUE TO ROLLING OF THE VESSEL.

Application filed August 31, 1921. Serial No. 497,419.

(GRANTED UNDER THE PROVISIONS OF THE ACT OF MARCH 3, 1921, 41 STAT. L., 1313.)

To all whom it may concern:

Be it known that I, OSCAR MARTIENSSSEN, physicist, citizen of the German Republic, and residing at Kiel, county of Schleswig-Holstein, State of Prussia, Germany, have invented certain new and useful Improvements in Arrangements on Gyrocompasses for Preventing Errors Due to Rolling of the Vessel (for which I have filed applications 10 in Germany, October 22nd, 1915, Patent Number 307,847, granted June 11th, 1918; Austria, October 25th, 1917, Patent Number 79,138, granted August 12th, 1919; England, July 10th, 1920, Patent Number 148,963, 15 granted September 15th, 1921), of which the following is a specification.

It is known that a gyro-compass on a ship, when affected by the rolling of the vessel, assumes a position that deviates more or less 20 from the meridian. This deviation is caused by oscillations which, when the ship rolls, are executed by the indicating movement of the gyro-compass about an axis lying parallel to the axis of the compass. Hence to 25 obviate the error of rolling of the gyro-compass it is necessary to suppress these oscillations as far as possible or to prevent them from occurring. This is effectually accomplished by making the natural periodic 30 time of these oscillations of the said movement much greater than the period of oscillation of the lurching of the ship. A known manner of fulfilling this requirement consists in distributing the masses in such a 35 way that, as regards oscillations about the axis of the gyro, the movement is almost balanced. Now by this measure a coincidence of the periodic time of the movement and a harmonic of the rolling motion, and hence 40 the occurrence of very large oscillations of the movement can be prevented, but it is difficult to attain a time period of oscillation appreciably greater than the period of 45 the rolling movement, without detriment to the stability of the movement required in practical use. The object of the invention is to fulfill the requirement first mentioned without involving the said disadvantage.

In accordance with the invention this is 50 accomplished by associating with the meridian gyro a gyro having a vertical spinning axis and by arranging the latter in such a manner that it does not hinder the

movements of elevation of the indicating gyro. The gyro with the vertical axis may 55 be associated with the indicating movement itself or, if the apparatus is equipped with a follow-up device that causes the movements of the gyro to be followed by members associated with it, it may be associated 60 with this device.

A constructional form of the invention is illustrated in the drawing in diagrammatical form in longitudinal vertical section.

a is the meridian gyro whose axis *b* extends at right angles to the plane of the drawing and which, together with its casing *c*, is adapted to turn on pivots *d* in a vertical ring *e*. These parts constitute the actual indicating movement which in turn is pivotally mounted at *y* in a second vertical ring *f*, and suspended by a wire *g*. This indicating movement is operatively connected to the ring *f* through a "following up" or turning device *h* of a character, shown 75 and described for instance in my copending application, Serial No. 497,417. Hence the ring *f* is continually caused to turn after, or follow the horizontal movements of the ring *e* so as to always keep these two rings in the 80 same relative positions. Therefore the position of the outer ring *f* indicates the position of the axis of the meridian gyro. A carrying member *i* is attached to the outer ring *f* which bears a compass chart *k* at its 85 upper end. The lower part of the carrying member *i* is arranged to act as a journal shaft for the entire movement of the compass, this journal shaft being arranged to revolve in a ball-bearing having two races 90 of balls *l*, *l'*, mounted in a bearing plate *m* which, in conjunction with a ring *n*, forms a gimbal. Mounted on the bearing plate *m* is a pointer *o* which serves as a steering mark. 95

The upper part of the carrying member *i* is adapted to receive the vertical gyro, referred to hereinbefore, as provided in accordance with the invention, this vertical gyro with its casing *p* being held in the vessel formed by the upper part *r* of the member *i* by pins *q*.

In the constructional form shown, the casing of the vertical gyro may be immovably fixed by the pins *q* to the casing *r*, because 105 this will not prevent the gyro *a* from swing-

ing into the proper elevation on its horizontal pivots d independently of the vertical gyro.

If it is immovably connected with its support, it will offer resistance to any force, which as in the case of rolling motions, tends to turn the device in the plane of the drawing (for instance in its cardanic suspension) and it will produce an effect by which this turning will not take place in the plane of the drawing, but if not entirely, at least partially at right angles thereto, i. e., substantially in the plane of elevation of the meridian gyro spinning axis. Besides, it will retard such turning or oscillations caused by the rolling motion of the ship. The motion of the vertical gyro resulting in a movement in a direction at right angles to the plane of the drawing, however, is of no consequence, because the meridian gyro which is mounted with its casing on horizontal pivots d , referred to hereinbefore, does not participate in this movement.

If it be desired to prevent this resulting motion of the structure carrying the meridian gyro, the vertical gyro should have its casing preferably pivoted on a horizontal axis extending at right angles to the spinning axis of the meridian gyro, so that the vertical gyro may now swing by itself in a direction at right angles to the plane of the drawing, without carrying the whole meridian gyro indicating device with it.

Thus if a loose coupling were established between the casing of the meridian gyro and the follow-up frame f by a damping means, the vertical gyro p could also be arranged to turn on its supports q as pivots. In this case the vertical gyro casing must be equipped with a bottom weight s , which may be vertically adjustable to properly adjust the center of gravity of this gyro below the pivotal axis. By these means the vertical gyro will always return with its spinning axis into vertical position, so that this position may be conveniently maintained.

I claim:

1. An arrangement for gyro compasses for preventing errors due to rolling of the vessel, the combination with a meridian gyro and suitable supporting means to permit its spinning axis to freely swing into the proper elevation, of a second gyro having a vertical spinning axis and being attached to said supporting means, to offer resistance to any force tending to turn said supporting means in a plane at right angles to the meridian compass axis, thereby precessing substantially in the direction of the plane of elevation of the meridian gyro spinning axis and thereby tending to suppress said turning movement.

2. An arrangement for gyro compasses for preventing errors due to rolling of the vessel, the combination with a meridian gyro and suitable supporting means to permit its spin-

ning axis to freely swing into the proper elevation, of a second gyro having a vertical spinning axis, and being pivotally attached to said supporting means upon a horizontal axis at right angles to the meridian gyro spinning axis, to offer resistance to any force tending to turn said supporting means in a plane at right angles to the meridian compass axis, thereby precessing substantially in the direction of the plane of elevation of the meridian gyro spinning axis, and thereby tending to suppress said turning movement.

3. An arrangement for gyro compasses for preventing errors due to rolling of the vessel, the combination with a meridian gyro and suitable supporting means to permit its spinning axis to freely swing into the proper elevation, of a second gyro having a vertical spinning axis, and being pivotally attached to said supporting means upon a horizontal axis at right angles to the meridian gyro spinning axis, to offer resistance to any force tending to turn said supporting means in a plane at right angles to the meridian compass axis, thereby precessing substantially in the direction of the plane of elevation of the meridian gyro spinning axis, and thereby tending to suppress said turning movement.

4. An arrangement for gyro compasses for preventing errors due to rolling of the vessel, the combination with a meridian gyro and suitable supporting means to permit its spinning axis to freely swing into the proper elevation, of a second gyro having a vertical spinning axis, and being pivotally attached to said supporting means upon a horizontal axis at right angles to the meridian gyro spinning axis, to offer resistance to any force tending to turn said supporting means in a plane at right angles to the meridian compass axis, thereby precessing substantially in the direction of the plane of elevation of the meridian gyro spinning axis, and thereby tending to suppress said turning movement, the center of gravity of said vertical gyro being disposed below its horizontal pivotal axis to cause the return of the gyro to its vertical position.

5. A gyro compass arrangement for preventing errors due to the rolling of the vessel, having a meridian gyro, means for pivotally supporting it to permit its spinning axis to swing to the proper elevation, rotatable means for supporting it to permit said axis to swing horizontally and means for causing said rotatable means to follow the horizontal movements of the meridian gyro, in combination with a gyro having a vertical spinning axis and being suitably attached to said rotatable supporting means, said vertical gyro offering resistance to any

- force tending to swing said rotatable means in a plane at right angles to the meridian compass axis, said vertical gyro thereby tending to precess substantially in the direction of the plane of elevation of the meridian gyro axis, and thereby hindering oscillations of the gyro compass about an axis extending in parallel to the meridian gyro spinning axis.
- 10 6. A gyro compass arrangement for preventing errors due to the rolling of the vessel, having a meridian gyro, means for pivotally supporting it to permit its spinning axis to swing to the proper elevation, rotatable means for supporting it to permit said axis to swing horizontally and means for causing said rotatable means to follow the horizontal movements of the meridian gyro, in combination with a gyro having a vertical spinning axis, and being pivotally attached to said rotatable supporting means on a horizontal axis at right angles to the meridian gyro spinning axis, said vertical gyro offering resistance to any force tending to swing said rotatable means in a plane at right angles to the meridian compass axis, said vertical gyro thereby tending to precess substantially in the direction of the plane of elevation of the meridian gyro axis, and thereby hindering oscillations of the gyro compass about an axis extending in parallel to the meridian gyro spinning axis, the center of gravity of said vertical gyro being adjustably disposed below its horizontal pivotal axis to cause the return of the gyro to its vertical position.
- 15 7. A gyro compass arrangement for preventing errors due to the rolling of the vessel, having a meridian gyro, means for pivotally supporting it to permit its spinning axis to swing to the proper elevation, rotatable means for supporting it to permit said axis to swing horizontally and means for causing said rotatable means to follow the horizontal movements of the meridian gyro, in combination with a gyro having a vertical spinning axis, and being pivotally attached to said rotatable supporting means on a horizontal axis at right angles to the meridian gyro spinning axis, said vertical gyro offering resistance to any force tending to swing said rotatable means in a plane at right angles to the meridian compass axis, said vertical gyro thereby tending to precess substantially in the direction of the plane of elevation of the meridian gyro axis, and thereby hindering oscillations of the gyro compass about an axis extending in parallel to the meridian gyro spinning axis, the center of gravity of said vertical gyro being adjustably disposed below its horizontal pivotal axis to cause the return of the gyro to its vertical position.
- 20 8. A gyro compass arrangement for preventing errors due to the rolling of the vessel, having a meridian gyro, means for pivotally supporting it to permit its spinning axis to swing to the proper elevation, rotatable means for supporting it to permit said axis to swing horizontally and means for causing said rotatable means to follow the horizontal movements of the meridian gyro, in combination with a gyro having a vertical spinning axis, and being pivotally attached to said rotatable supporting means on a horizontal axis at right angles to the meridian gyro spinning axis, said vertical gyro offering resistance to any force tending to swing said rotatable means in a plane at right angles to the meridian compass axis, said vertical gyro thereby tending to precess substantially in the direction of the plane of elevation of the meridian gyro axis, and thereby hindering oscillations of the gyro compass about an axis extending in parallel to the meridian gyro spinning axis, the center of gravity of said vertical gyro being adjustably disposed below its horizontal pivotal axis to cause the return of the gyro to its vertical position.
- 25 9. A gyro compass arrangement for preventing errors due to the rolling of the vessel, having a meridian gyro, means for pivotally supporting it to permit its spinning axis to swing to the proper elevation, rotatable means for supporting it to permit said axis to swing horizontally and means for causing said rotatable means to follow the horizontal movements of the meridian gyro, in combination with a gyro having a vertical spinning axis, and being pivotally attached to said rotatable supporting means on a horizontal axis at right angles to the meridian gyro spinning axis, said vertical gyro offering resistance to any force tending to swing said rotatable means in a plane at right angles to the meridian compass axis, said vertical gyro thereby tending to precess substantially in the direction of the plane of elevation of the meridian gyro axis, and thereby hindering oscillations of the gyro compass about an axis extending in parallel to the meridian gyro spinning axis, the center of gravity of said vertical gyro being adjustably disposed below its horizontal pivotal axis to cause the return of the gyro to its vertical position.
- 30 10. A gyro compass arrangement for preventing errors due to the rolling of the vessel, having a meridian gyro, means for pivotally supporting it to permit its spinning axis to swing to the proper elevation, rotatable means for supporting it to permit said axis to swing horizontally and means for causing said rotatable means to follow the horizontal movements of the meridian gyro, in combination with a gyro having a vertical spinning axis, and being pivotally attached to said rotatable supporting means on a horizontal axis at right angles to the meridian gyro spinning axis, said vertical gyro offering resistance to any force tending to swing said rotatable means in a plane at right angles to the meridian compass axis, said vertical gyro thereby tending to precess substantially in the direction of the plane of elevation of the meridian gyro axis, and thereby hindering oscillations of the gyro compass about an axis extending in parallel to the meridian gyro spinning axis, the center of gravity of said vertical gyro being adjustably disposed below its horizontal pivotal axis to cause the return of the gyro to its vertical position.

In testimony whereof I affix my signature in presence of two witnesses.
